UNITED STATES PATENT OFFICE.

RICHARD O. JONES, OF DAYTON, OHIO, ASSIGNOR, BY MESNE ASSIGNMENTS, TO THE COMPUTING SCALE COMPANY, OF DAYTON, OHIO, A CORPORATION OF OHIO.

CENTRIFUGAL PUMP.

957,682.

Specification of Letters Patent. Patented May 10, 1910.

Application filed November 28, 1908. Serial No. 464,957.

To all whom it may concern:

Be it known that I, RICHARD O. JONES, a citizen of the United States, residing at Dayton, in the county of Montgomery and State of Ohio, have invented certain new and useful Improvements in Centrifugal Pumps, of which the following is a full, clear, and exact description.

This invention relates to centrifugal pumps of the single stage type, and one of the principal objects is to provide a pump of high efficiency capable of running at high speed and on low lifts or pressures.

In general terms the invention comprises a plurality of impellers mounted upon a common impeller shaft and having a common volute discharge passage, the total water capacity being divided up among the various impellers so as to get large capacity and at the same time keep the impeller diameters small. As the lift to which the water may be delivered depends upon the outside diameter of the impellers, it is manifest that the impellers must be very small in diameter when it is desired to run them on low lifts and at high speeds. The high speed is an important consideration because of the increase in pump efficiency which results therefrom and likewise from the increased efficiency of the motive power when a steam turbine is used as such a driving means. The inlet or inside diameter of the impeller is governed by the quantity of water passing into the impeller at a proper velocity. Therefore, by dividing the water up into the various intake openings of a plurality of impellers, this total intake capacity is multiplied whereas the inlet diameter of each impeller is kept small and therefore with outside diameter comparatively small.

With the above mentioned objects in view, and with the further desiderata of securing a construction having the advantages of simplicity, compactness, economy and accessibility, the present invention comprises the combination of mechanisms hereininafter set forth and a preferred form of embodiment of which is shown in the attached drawings forming part of the specification.

Of said drawings, Figure 1 represents a vertical cross section through the pump containing these improvements; and Fig. 2 represents a detailed view of one of the diffusion rings.

Upon the transverse revoluble shaft 20 are mounted two double impellers 21 and 22. The impeller 21, on the left of Fig. 1, is formed with two intake openings on opposite sides thereof, namely, 23 and 24; likewise the right hand impeller is of the double type having two opposite intake openings 25 and 26. Both these impellers are suitably keyed or otherwise fastened to the shaft 20 so as to revolve therewith, and the impellers are of substantially the same size and construction.

The water to be delivered to the pump comes in through the main suction pipe 30 and divides through the Y pipes 31 and 32. The suction pipe 31 leads to the suction head 33 on the left hand side of the cylinder casting, this suction head surrounding the left hand impeller 21 so as to deliver water to its outside intake opening 23. Similarly, the suction pipe 32 on the right, delivers water to the suction head 34 which surrounds and delivers water to the outside intake opening 25 of the right hand impeller 22.

Surrounding the impeller 21 is a diffusion ring 41 and surrounding the impeller 22 is the diffusion ring 42. These diffusion rings are formed with the usual diffusion vanes 43 carried spirally around the diffusion ring 41 from the impeller periphery to the outer periphery of the diffusion ring so as to form water passages 44 therebetween from inner to outer periphery (see Fig. 2). These diffusion rings 41 and 42 are bent laterally so as to converge from the two separated impellers toward a common discharge periphery as at 45. Surrounding this common periphery of the diffusion rings is the volute casing 50, which as usual is substantially circular in cross section but increases in diameter from its smallest or contracted portion to its largest portion where the water is discharged into the main discharge pipe.

In order to conduct the suction water to the inside intake openings 24 and 26 of said impellers 21 and 22, the aforesaid diffusion rings 41 and 42 are cored transversely with suction openings 60, shown both in Figs. 1 and 2. These suction openings conduct the suction water from one side of the diffusion ring to the other thereby forming connecting water channels leading from the outside suction heads to the respective inside intake openings of said impellers. By this means

the water is simultaneously delivered to both the intake openings of both impellers.

It will be seen from Fig. 1 that the impeller casings unite between the two impellers and form an intermediate common wall or partition, thereby forming a separating wall between the transversely cored passages or openings 60 at their central approach to the said interior or inside intake openings 24 and 26 of the impellers.

The arrows on Fig. 1 show the direction of the water flow as follows:—from the main suction pipe through the Y pipes 31 and 32 into the suction heads on opposite sides of the cylinder and thus into the outside intake openings 23 and 25 of the two impellers. Then at the same time this suction water flows through the water channels 60 formed in the diffusion rings and thence supplies the inside intake openings 24 and 26. The water thus being taken in from both sides of both impellers, flows through the water passages 44 of the diffusion rings to join at the common periphery thereof and be discharged into the volute casing 50 which it traverses circularly in the usual manner and is then discharged from the pump.

It has heretofore been suggested to use what practically amounts to two separate and distinct centrifugal pumps having a common operating shaft, with each separate pump complete in itself with its own volute casing, but having a common suction supply for the two separate pumps. The present invention, however, relates to an entirely different form of construction in which the suction pipes deliver water individually to the various inlets or intake openings of the plurality of impellers and then there is but a single volute casing common to and connected with these impellers. In the present form, in which two double impellers are shown side by side, the suction water is first divided into two equal parts, one-half going to each side of the pump. When each half of the water reaches its respective suction head it is again divided into two equal parts thus supplying each side of each impeller with one-fourth of the total capacity of the pump. There being two separate diffusion ring castings one-fourth of the total quantity of water passes transversely through the holes cored into the diffusion ring castings. Thus the suction water passes through the diffusion rings at right angles to the discharge water which is confined within the water passages formed by the diffusion vanes. It will be noted that this construction is not that of a series pump, even though it has a series of impellers mounted on the same shaft, for both impellers deliver water against the same lift or head. The result of the construction is that since the total water

capacity is divided up into four parts, each side of each of the double impellers taking one-fourth of the total capacity, the inside diameters of the impellers can thereby be kept small. This enables the outside impeller diameter to be correspondingly small so that the impellers may be run at high speed against a low lift with large capacity and high efficiency.

It is to be understood that the form of mechanism shown and described herein is one which is adopted as a preferred form for attaining the objects desired, but that this form may be varied without departing from the scope of the invention as set forth in the claims which follow.

I claim:

1. In a centrifugal pump, the combination with a plurality of double impellers mounted upon a common impeller shaft and revolute therewith, of suction pipes and water passages for conducting water to all the intake openings on the opposite sides of said double impellers; and a single discharge casing common to and connected with said impellers.

2. In a centrifugal pump, the combination with a plurality of double impellers mounted upon a common impeller shaft and revolute therewith, of suction pipes and water passages for conducting water to all the intake openings on the opposite sides of said double impellers; a diffusion ring surrounding each of said double impellers and all converging to a common discharge periphery; and a single discharge casing common to and surrounding said diffusion rings at their common discharge periphery, and serving as a common discharge for all said impellers.

3. In a centrifugal pump, the combination with a cylinder casing inclosing two double impellers mounted side by side upon a common impeller shaft and revolute therewith, of double suction pipes leading to suction heads on opposite sides of the cylinder casing, said pipes connecting with the outside intake openings of said impellers; water channels leading through said cylinder casing from the outside suction heads to the respective inside intake openings of said impellers; and a single discharge casing common to and connected with said impellers.

4. In a centrifugal pump, the combination with a cylinder casing inclosing two double impellers mounted side by side upon a common impeller shaft and revolute therewith, of double suction pipes leading to suction heads on opposite sides of the cylinder casing, said pipes connecting with the outside intake openings of said impellers; a diffusion ring for each of said impellers both converging to a common discharge periphery; water channels leading from said

outside suction heads through said diffusion rings to the respective inside intake openings of said impellers; and a single volute casing common to and surrounding said diffusion rings at their common discharge periphery, said volute serving as a common discharge for both said impellers.

5. In a centrifugal pump, the combination with a pair of double closed impellers 10 mounted on a revoluble impeller shaft, and a suction pipe and head connected with the outside intake opening of each of said impellers; of a casing surrounding each of said impellers and having suction passages cored

transversely therethrough to connect with 15 the interior intakes on the opposite sides of the impellers; said impeller casings uniting between the two impellers in an intermediate common partition forming a separating wall between said transversely cored passages at their central approach to said interior intakes.

In testimony whereof I affix my signature in the presence of two subscribing witnesses.

RICHARD O. JONES.
